Patented Mar. 16, 1915.

UNITED STATES PATENT OFFICE.

EMIL BOMMER, OF NEW YORK, N. Y.

SPRING-HINGE.

1,131,667.

Specification of Letters Patent. Patented Mar. 16, 1915.

Application filed April 15, 1913, Serial No. 761,140. Renewed October 24, 1914. Serial No. 868,517.

To all whom it may concern:

Be it known that I, EMIL BOMMER, a citizen of the United States of America residing in New York, in the borough of Brooklyn, county of Kings, and State of New York, have invented certain new and useful Improvements in Spring-Hinges, of which the following is a specification.

This invention relates to an improved spring-hinge of that type which is attached to the lower corner of a door and operated in connection with a stationary socket-plate attached to the floor below the hinge, and with a socket in the upper corner of the door connecting with a pivot of the door-casing.

The invention relates more specifically to certain improvements in the spring-hinge for which Letters Patent were granted to me heretofore on January 10, 1911, No. 981,053, said improvements being designed with a view of simplifying the construction of the hinge by dispensing with a number of parts contained in the same, while accomplishing the same result, namely, the swinging of the door in either direction and closing it under the influence of its spring-power, and the release of the spring-power from the spring-hinge for permitting the placing of the door into open position and holding it yieldingly in this position at either side of the door-casing when the door is not desired to be swung under the action of the spring into closed position; and for this purpose the invention consists of a spring-hinge of the type referred to which will be fully described hereinafter and finally pointed out in the claims.

In the accompanying drawing, Figure 1 represents a side-elevation of a door with my improved spring-hinge shown in position at the lower corner thereof. Fig. 2 is a horizontal section on line 2, 2, Fig. 1, drawn on a larger scale, Fig. 3 is a vertical longitudinal section through the spring-hinge and its floor-plate, Fig. 4 is a vertical transverse section on line 4, 4, Fig. 3, taken in the direction of the arrows, and in a plane at right angles to that of Fig. 3, Fig. 5 is also a vertical transverse section, taken on line 5, 5, Fig. 3, in the direction of the arrows, so as to show the operating levers for setting the slide-plate by which the spring-power is released from the swing-door, Figs. 6 and 7 are respectively detail elevations of the lower and upper ends of

the stationary pintle, showing the horizontal guide-grooves and the connecting vertical guide-grooves on the same, and Figs. 8 and 9 are detail horizontal sections 60 through the pintle and its spring-holders respectively on lines 8, 8 and 9, 9, Fig. 3.

Similar letters of reference indicate corresponding parts throughout the different figures of the drawing.

Referring to the drawing, D represents a swing-door and D¹ the casing of the same. The lower rear-corner of the door is provided with a mortise of sufficient size for inserting a spring-hinge therein, which corresponds in size and strength to the size and weight of the door. Below the spring-hinge, and axially in line with the pintle P of the same, is arranged a floor-plate B, which is attached by means of fastening 70 screws b to the floor. The floor-plate B is provided with a tapering socket b¹ of square cross-section for receiving the lower corresponding-tapered and squared end p of the pintle P and holding it thereby in a non-rotatable position. On the lower end of the pintle P is journaled an oblong hinge-frame F which is provided at its upper end with a hole into which, and into a socket at the upper end of the pintle P, is inserted an auxiliary smaller pintle p¹ by which the connection of the pintle with the hinge-frame F of the spring-hinge is made. The hinge-frame F is provided with a vertical extension f at its upper and with a horizontal extension f¹ at its lower end, which ends are attached to the door by means of fastening screws f² as shown in Fig. 3.

The hinge-frame F is preferably made of cast-metal and covered at its outer vertical portion by a sheet-metal facing f³ which is lapped inwardly over the edges of the outer wall of the frame, as shown in Figs. 2 and 3. The spring-hinge is inclosed by sheet-metal side-plates f⁴ which are attached to the lower corner of the door and which serve to protect the interior parts of the spring-hinge against the ingress of dust. On the pintle P is arranged, at the interior of the frame F, a coil-spring S of sufficient power to return the door from its open to its closed position. The lower end of the coil-spring S is bent downwardly and inserted into a recess h⁷ of the lower spring-holder H, while the upper end of the coil-spring S is provided with an upwardly-bent end which is inserted into a recess h⁸ of the upper spring-

holder H^1 in the usual manner. The lower spring-holder H is provided with a lug h^5 having an inclined and a vertical face on its sides. The upper spring-holder H^1 is provided with radial holes h^6 for inserting a tension-pin h by which the coil-spring is set to tension in the usual manner. Above the upper spring-holder H^1 is arranged a tension-collar H^2 having a lug h^2 with one vertical and one inclined face on its sides, said lug having a downwardly-extending stop h^x adapted to receive the recoil of the hinge-spring S upon the tension-pin h of the upper spring-holder H^1 after the spring is set to tension and to transmit the same by interior pins h^3 , h^4 of the tension-collar H^2 and of the lower spring-holder H to the ends or stops p^6 and p^7 of horizontal grooves p^2 and p^3 on the pintle P , and hold said interior pins h^3 and h^4 in contact therewith in order to retain the door in its normally closed position and to locate the lug h^5 of the lower spring-holder and the lug h^2 of the tension-collar in correct alinement for connection and disconnection with the lugs i and i^1 of a slide plate I of the hinge-frame F . When the door is swung into open position in one or the other direction the recoil of the hinge-spring S again returns the same to its normally closed position. The upper and lower ends of the pintle P are preferably made larger in diameter than the middle portion for arranging thereon the horizontal and vertical grooves p^2 , p^3 and p^4 , p^5 at the upper and lower ends of the same. The inwardly-extending pin h^3 of the tension-collar H^2 is adapted to travel in the horizontal groove p^2 in the upper enlarged portion of the pintle P , while the inwardly-extending pin h^4 of the lower spring-holder H is adapted to travel in the horizontal groove p^3 in the lower enlarged portion of the pintle P . The length of the horizontal grooves p^2 , p^3 is proportioned to the angle through which the door is desired to be opened, one horizontal groove extending in one, the other in the opposite direction from the ends or stops p^6 and p^7 at the farther end of each horizontal guide-groove so as to provide for opening the door in one or the opposite direction. The contact faces of the lugs h^5 and h^2 on the spring-holder H and tension-collar H^2 are held at all times when the coil-spring S is under tension in correct position or vertical alinement with each other, by the abutting of the interior pins h^3 and h^4 against the ends or stops p^6 and p^7 of the horizontal grooves p^2 and p^3 .

Between the upper horizontal portion of the hinge-frame F and the tension-collar H^2 on the auxiliary pintle p^1 , an antifriction-washer or ball-bearing of any suitably construction, as shown for instance at a , may or may not be interposed in order to take up the weight of the door upon the pintle and

permit the easy and noiseless motion of the spring-hinge when opening or closing the door. The outer side of the inner vertical wall of the hinge-frame F is recessed and its recessed portion covered by a plate f^4 , which is attached by means of screws f^5 to the hinge-frame, and between which and the hinge-frame is guided a slide-plate I that is provided with lugs i and i^1 at the upper and lower ends, said lugs projecting inwardly through openings i^3 and i^4 which are located in the upper and lower ends of the inner vertical wall of the hinge-frame F . The lugs i and i^1 are located respectively to the right and left of the vertical central line of the inner wall of the hinge-frame F and are guided along cheeks f^6 and f^7 on said vertical wall adjacent to the openings i^3 and i^4 , said cheeks f^6 and f^7 serving to increase the bearing surface for the lugs i and i^1 of the slide-plate I against the pressure of the coil-spring and permitting the sliding movement of the slide-plate I without straining the same. Within a recess of the inner vertical wall of the hinge-frame F adjacent to the slide-plate I is seated a helical spring i^2 , the upper end of which abuts against the upper end of the recess, while the lower end abuts on a shoulder i^5 of the slide-plate I , the spring exerting a sufficient pressure on the slide-plate for holding it in position for engaging the vertical faces of the lugs on the spring-holder H and tension-collar H^2 when the door is to swing and close under the influence of the spring S of the hinge, or to be held in or latched in open position disconnected from the action of the spring S .

Adjacent to the shoulder i^5 of the slide-plate I is a stud i^6 , which projects through a slot m of the inner vertical portion of the hinge-frame F in the vertical central line thereof, said stud i^6 being guided in the slot m . The lower edge of the stud i^6 is provided with abutments m^1 , the lower faces of which are suitably inclined to be acted upon by levers L , which are fulcrumed at K , below the opening m , to the inside of the inner vertical wall of the hinge-frame F . The levers L extend through slots in the sheet-metal side-plates f^3 and are provided at their upper ends with bent-over portions l , which are suitably arranged for convenient operation either by the foot or by the hand from either side of the door, whenever the spring-power of the spring-hinge is to be disconnected by passing the lugs i and i^1 of the slide-plate I over the inclined faces of the lugs h^5 and h^2 of the lower spring-holder and tension-collar for holding the door open to one side or the other. When the spring-power of the spring-hinge is to be restored, the lugs i^1 and i of the slide-plate I are returned automatically by the act of closing the door into reengagement with the vertical faces of the lugs by forcing

the lugs over the inclined faces of the lugs of the lower spring-holder H and of the tension-collar H² against the downward resistance of the helical spring i² of the slide-plate and the angle of inclination of the lugs.

The levers L are arranged in a plane at right angles to the door and have overlapping and underlapping heel-shaped ends l¹ which are extended beyond their fulcrum K so as to raise the abutments m¹ of the stud i⁶ of the slide-plate I when the lever L at one or the other side of the door is depressed. The lower portions of the levers are provided with stops l² and l³ to limit their downward movement so that they shall not reach a dead center; when one of the levers is depressed the other lever is free to recede upwardly and inwardly till its bent-over end l is stopped by striking against the side-plate f³ to prevent marring of the casting by the outwardly-projecting ends of the levers L when the door is in fully opened position.

The improved spring-hinge is operated as follows: When the projecting lugs i¹ and i of the slide-plate I are in engagement with the vertical faces of the lugs h⁵ and h² on the spring-holder H and tension-collar H², the spring-hinge acts in the usual manner for swinging the door from its open into closed position under the recoil of the spring, but when it is desired to remove the spring-power from the hinge, either one or the other of the fulcrumed operating levers L is depressed (preferably by foot), whereby the slide-plate I with its lugs is raised by the action of one of the heels i¹ of the levers L on the abutment m¹, so that the lugs i¹ and i can be passed over to and down the inclined faces of the lug h⁵ of the lower spring-holder H and the lug h² of the tension-collar H², permitting thereby the hinge-frame to swing on the pintle P disconnected from the action of the coil-spring.

While the vertical faces of the lugs h⁵ and h² of the lower spring-holder H and tension-collar H² are in engagement with the lugs i¹ and i of the slide-plate I, the interior pins h³ and h⁴ are in engagement with the ends or stops p⁶ and p⁷ of the horizontal grooves and the parts are held in contact by the recoil of the tension of the hinge-spring S thereby retaining the door in its normally-closed position. When the door is then opened in one or the other direction the tension of the coil-spring is increased and the door is returned to its normal closed - position by the recoil of the spring when the door is released.

When the slide-plate I is raised, the lugs i¹ and i are passed over and then along the inclined faces of the lugs h⁵ and h², being then out of engagement with the vertical faces of the lugs h⁵ and h², so that the door

is not acted upon by the coil-spring S which is locked dormant on the pintle P by the recoil of the spring forcing the interior pins h³ and h⁴ into the ends or stops p⁶ and p⁷ of the horizontal grooves p² and p³, and the door is held in a more or less yielding open position, the degree of the yield being determined by the degree of inclination of the inclined faces of the lugs h⁵ and h², modified by the strength, power or degree of resistance of the helical spring i² of the slide-plate. In case the inclination of the lugs h⁵ and h² approaches 90 degrees, the door would be positively locked in open position until the slide-plate I is again raised by depressing one of the operating levers L. As soon as the door is moved back into closed position, the lugs i and i¹ of the slide-plate I are thereby forced to pass along and over the inclined faces and upper ends of the lugs h² and h⁵ and to reengage thereby under the pressure of the spring i² of the slide-plate I the vertical faces of said lugs, so as to restore the spring-power again to the hinge and door, and retain the door under the influence of the hinge-spring S in its normally closed position. The operating levers L are returned by the action of the helical spring i² on the abutments m¹ and held in an upwardly-inclined position at each side of the door by the spring i².

The parts of the spring-hinge, that is to say, the spring-holder H, the coil-spring S, the spring-holder H¹ and the tension-collar H², are assembled in their proper position on the pintle P by passing the pintle P through the journal-opening in the lower portion of the hinge-frame F, the vertical grooves on the pintle P serving then for permitting the slipping in of the interior pins h³ and h⁴ of the spring-holder H and tension-collar H² into their proper position in the horizontal grooves p² and p³ of the pintle P. The auxiliary pintle p¹ is then inserted through the hole in the upper part of the hinge-frame F into the socket-hole in the upper part of the pintle P.

The support of the pintle P in rigid position in the socket b¹ of the floor-plate B and the arrangement of the horizontal grooves p² and p³ in the upper and lower parts of the pintle P admit of a greatly simplified construction of the spring-hinge, assure the proper alignment of the vertical faces of the lugs h² and h⁵ by the action of the coil-spring S upon the interior pins h⁴ and h³ of the spring-holder H and tension-collar H² when the hinge is connected or disconnected from the closing action of the spring, and permit the swinging of the hinge-frame F directly upon the pintle P, dispensing with the stationary frame used in the prior patent referred to, while at the same time a stronger and more compact construction of the hinge is obtained.

Reference is made to my copending application which claims the hinge structure without the spring-releasing means, said application being identified by Ser. No. 761,139, filed April 15, 1913.

I have shown an embodiment of my invention, but changes may be made therein without departing from the spirit of the invention as defined by the appended claims.

10 I claim:

1. A spring-hinge, comprising a non-rotatable pintle secured to the floor and provided with horizontal grooves in its upper and lower portions, a hinge-frame attached to

15 the door and journaled on said pintle, a lower spring-holder and an upper spring-holder on said pintle, a coil-spring engaging said spring-holders, a tension-collar adjacent to the upper spring-holder, the lower

20 spring-holder and the tension-collar being provided with exterior lugs and with inwardly-projecting pins engaging the horizontal grooves of the pintle, a spring-actuated slide-plate guided on the inner wall of

25 the hinge-frame and provided with lugs at its upper and lower ends, levers fulcrumed to said hinge-frame, and means between the levers and slide-plate adapted for raising the slide-plate with its lugs out of engagement

30 or lowering them into engagement with the exterior lugs on the lower spring-holder and tension-collar.

2. A spring-hinge, comprising an oblong hinge-frame secured to the door, a floor-

35 plate, a pintle non-rotatably socketed in said floor-plate and provided with horizontal recesses in its lower and upper portions, a lower spring-holder and an upper spring-holder on said pintle, a coil-spring applied

40 to said spring-holders, a tension-collar adjacent to the upper spring-holder, the lower

spring-holder and the tension-collar being provided with exterior lugs and with inwardly-projecting pins, a spring-actuated

45 slide-plate guided on the inner wall of said hinge-frame and provided with projecting lugs for engaging the lugs of the lower spring-holder and tension-collar, abutments connected with said slide-plate, operating

50 levers fulcrumed on the hinge-frame below the abutments and adapted to raise the same together with the slide-plate from either side of the door.

3. A spring-hinge, comprising an oblong

55 hinge-frame adapted to be secured to the door, a floor-plate provided with a socket, a pintle non-rotatably secured to said floor-plate, a lower spring-holder and an upper spring-holder on said pintle, a coil-spring

60 connected at its opposite ends with the spring-holders, a tension-collar adjacent to the upper spring-holder, said pintle being provided with vertical grooves at the upper

65 and lower ends of the pintle and with horizontal grooves connected with the vertical

grooves, inwardly-projecting pins on the lower spring-holder and tension-collar adapted to engage said horizontal grooves, exterior lugs having straight and inclined side-faces on the lower spring-holder and 70 tension-collar, a slide-plate guided vertically in the inner wall of the hinge-frame and provided with inwardly-projecting lugs at its lower and upper ends, guide-cheeks on the inner wall of the hinge-frame along- 75 side of said lugs, spring-actuated abutments connected with said slide-plate, and operating levers fulcrumed to the hinge-frame below said abutments and adapted to raise the same together with the slide-plate from 80 either side of the door.

4. A spring-hinge, comprising an oblong frame adapted to be secured to the door, a socketed floor-plate, a pintle non-rotatably

85 secured to said floor-plate, a lower spring-holder and an upper spring-holder on said

pintle, the pintle being provided with lower

and upper enlarged portions having vertical

grooves and horizontal grooves connected

therewith, a tension-collar adjacent to the 90

upper spring-holder, exterior lugs on the

lower spring-holder and the tension-collar, a

coil-spring connected at opposite ends with

the lower and upper spring-holders, inwardly-extending pins on the lower spring- 95

holder and tension-collar projecting into

said horizontal grooves, a spring-actuated

slide-plate guided vertically in the inner

wall of the frame, spring-actuated abutments guided on the inner wall of the hinge- 100

frame and connected with said slide-plate,

and operating levers fulcrumed below said

abutments and provided with upwardly-ex- 105

tending heels adapted for raising the same

together with the slide-plate from either

side of the door.

5. In a spring-hinge, the combination of

a non-rotatable pintle, a lower spring-holder

having an exterior lug with a vertical and

an inclined face, an upper spring-holder, a

coil-spring connected thereto, a tension-collar adjacent to the upper spring-holder and

provided with an exterior lug having a vertical and an inclined face, a hinge-frame

journaled on said pintle, a spring-actuated

slide-plate guided on the inner wall of said

hinge-frame, said slide-plate having lugs at

its upper and lower ends, one lug being lo-

cated to the right and the other to the left

of the vertical center-line of the hinge-

frame, a stud on the slide-plate, abutments

on said stud, and levers fulcrumed to the in-

ner wall of the hinge-frame below said stud

and provided with upwardly-extending heels

engaging said abutments, the lugs on the

slide-plate being adapted to be raised by the

levers out of the path of the lugs on the

lower spring-holder and tension-collar and

swung with the hinge-frame into contact

with the inclined faces of the same until

forced back again over the inclined faces to their former position on the vertical faces when the door is closed.

6. A spring-hinge, comprising a non-rotatable pintle secured to the floor and provided with horizontal grooves in its upper and lower portions and with a socket in its upper end and an auxiliary pintle connecting the upper end of the pintle with the upper part of the hinge-frame, a hinge-frame attached to the door and journaled on said pintle, a lower spring-holder and an upper spring-holder on said pintle, a coil-spring engaging said spring-holders, a tension-collar adjacent to the upper spring-holder, the lower spring-holder and the tension-collar being provided with exterior lugs and with inwardly-projecting pins engaging the horizontal grooves of the pintle, a spring-actuated slide-plate guided on the inner wall of the hinge-frame and provided with lugs at its upper and lower ends, and means between the hinge-frame and slide-plate adapted for raising the lugs of the slide-plate out of engagement with the exterior lugs on the lower spring-holder and tension-collar or lowering them into engagement therewith.

7. In a spring-hinge having a movable frame and a permanently fixed pintle, the combination of spring-holders, each revolvable in one direction, a coil-spring between said holders, means on the frame for engaging both the spring-holders for tensioning the spring when the door is opened, means for disconnecting said last-named means simultaneously from both the spring-holders when it is desired to use the door without the spring, and means for automatically reconnecting both of said spring-holders when the door is brought into closed position.

8. In a spring-hinge having a movable frame and a fixed pintle, the combination of revolvable spring-holders mounted on the pintle, a coil-spring attached to the spring-holders, a tension-collar for one of the spring-holders, a lug on the tension-collar, a lug on one of the spring-holders, means for disengaging the lugs from the frame for holding the door in open position, and means for automatically reengaging the lugs with the frame when closing the door.

9. In a spring-hinge, the combination of spring-actuated spring-holders, a tension-collar for one of the spring-holders, a lug on the tension-collar, a lug on one of the spring-holders, each of said lugs having a vertical and an inclined face, a spring-actuated slide-plate having lugs, and levers for disengaging the lugs of the slide-plate from the vertical faces of the lugs of the spring-holder and tension-collar for permitting their movement over to the inclined faces of said lugs, the degree of incline of the in-

clined faces of said lugs of the spring-holder and tension-collar determining the amount of resistance against the closing door.

10. In a spring-hinge, the combination of spring-actuated spring-holders, a tension-collar for one of the spring-holders, a lug on the tension-collar and a lug on one of the spring-holders, each of said lugs having a vertical and an inclined face, a slide-plate having lugs, levers for disengaging said slide-plate lug from the vertical faces of the lugs of the spring-holder and tension-collar for permitting their movement over to the inclined faces of said lugs, and a spring on the slide-plate whose reaction is opposed to the upward movement of the lugs of the slide-plate over the inclined faces of the lugs of the spring-holder and tension-collar until the lugs of the slide-plate come into alignment with and are depressed by said spring into spring-reacting engagement with the vertical faces of the lugs of the spring-holder and tension-collar, the strength or resistance of the spring of the slide-plate being proportioned, in connection with the degree of incline of the inclined faces of the lugs of the spring-holder and tension-collar, to the amount of yield desired when restoring the hinge to spring-reacting engagement.

11. In a spring-hinge having a movable frame, a non-rotatively fixed pintle, revivable spring-holders mounted on said pintle, a coil-spring between the spring-holders, the combination of lugs one for each spring-holder, each having an inclined face and a vertical face, the inclined faces being inclined in opposite directions, and a movable lug on the frame for each of said spring-holder lugs for engagement therewith, and adapted to ride on the corresponding inclined face and to be brought in locking engagement with the vertical face thereof.

12. In a spring-hinge having a movable frame, a non-rotatively fixed pintle, revivable spring-holders mounted on said pintle and a coil-spring between the spring-holders; the combination of lugs one for each spring-holder each having an inclined face and a vertical face, the inclined faces being inclined in opposite directions to each other, a movable lug on the frame for each of said spring-holder lugs for engagement therewith, and adapted to ride on the corresponding inclined face, and to be brought in locking engagement with the vertical face thereof, a pivoted member extending exteriorly of the frame for moving the movable lug out of engagement with the vertical face of the spring-holder lug, and a spring for returning the movable lug to locking position with the vertical face after it leaves the inclined face of the spring-holder lug.

13. In a spring-hinge having a movable frame, a non-rotatively fixed pintle, revolu-

- ble spring-holders mounted on said pintle and a coil-spring between the spring-holders, the combination of lugs, one for each spring-holder, each having an inclined face 5 and a vertical face, the inclined faces being inclined in opposite direction to each other, and a lug on the frame for each of said spring-holder lugs for engagement therewith and adapted to ride on the corresponding inclined face and to be brought in locking engagement with the vertical face thereof; a connecting member movable in the frame for the said frame lugs, an abutment on the connecting member intermediate said 10 frame lugs, members pivoted to the frame engaging said intermediate abutment for raising it, the connecting member and the lugs thereon, and a spring for returning said last-named lugs, connecting member, intermediate abutment and pivoted members to their original position.
14. In a spring-hinge having a movable frame, a non-rotatively fixed pintle, revolvable spring-holders mounted on said pintle, a 15 coil-spring between the spring-holders, the 20
- 25

combination of lugs one for each spring-holder, lugs on the frame for each of said spring-holder lugs, a connecting member for the last-named lugs on the frame, an abutment intermediate said lugs arranged on 30 said connecting member, provided with oppositely inclined surfaces, members pivoted to the frame engaging said intermediate abutment for raising it, the connecting member and the lugs thereon, heels on either 35 of said pivoted members for engaging the inclined surfaces of the intermediate abutment, stops on the lower portion of the pivoted members for limiting the movement of either thereof, and a spring for returning 40 the pivoted member and connecting member for the lugs to their original position.

In testimony, that I claim the foregoing as my invention, I have signed my name in presence of two subscribing witnesses.

EMIL BOMMER.
